WATCH MECHANISM

Solomon Cochin, Detroit, Mich., assignor of one-third to Samuel N. Kagan and one-third to Minnie Cutler, both of Detroit, Mich.

Application July 29, 1932. Serial No. 625,597

7 Claims. (Cl. 58-67)

The present invention relates to watch mechanisms or movements and more especially to improvements in winding posts or stems therefor.

Heretofore it has been customary in such mechanisms to provide the stem shaft with annular shoulders with which cooperates a finger carried by a detent or lever element which lever is adapted to operate clutch mechanism throwing into and out of operation the winding apparatus and setting apparatus. As the finger slides between the two shoulders there is of course considerable wear thereon during winding and setting operations and eventually play develops to such an extent that the mechanism ceases to be operative or becomes easily broken.

Among the objects of the present invention is to overcome these defects and provide a more rugged element for taking the wear and to reduce to a minimum or entirely eliminate any wear on the finger which is, as stated above, secured to the lever or detent.

Other objects will readily occur to those skilled in the art upon reference to the following description and the accompanying drawing in which

Fig. 1 illustrates a portion of a suitable watch mechanism showing the parts in setting position.

Fig. 2 is a similar view showing the parts in winding position.

Fig. 3 is an enlarged view of a portion of Fig. 2.

Fig. 4 is a section on the line 4-4 of Fig. 3.

Fig. 5 is a section on the line 5-5 of Fig. 3.

Fig. 6 is a detail in perspective view, and

Fig. 7 is a view similar to Fig. 5 but showing a modification.

Fig. 8 is a similar view of another modification, and

Fig. 9 is a view in elevation of a stem assembly.

In the drawing a suitable frame for the watch movement is indicated at 10 and at 11 is shown one of the train of gears having to do with the hands of the watch and the setting thereof. At 12 is shown a suitable milled knob or cap piece

threaded upon the end of the stem 13 which carries splined thereon a clutch member 14 slideable lengthwise of the stem 13 to engage the crown gear 15 with the small gear 16 which latter meshes with one of the gear 11 and thereby permits the operator to move the hands of the watch when the clutch is in this lower position. The clutch member 14 when moved to its upper position as indicated in Fig. 2 cooperates with its mating element carried by gear

17 which is a part of the gear train for winding the watch.

This clutch element 14 is carried in a suitable slip ring in the end of a supporting spring member 20 fixed on the frame as at 21, the spring member 20 serving to guide the clutch in its up and down movements and tending to thrust it into the winding position of Fig. 2.

In the particular mechanism shown the clutch member 14 is moved up and down on the stem 13 by means of a detent or bell crank lever 25 pivotally mounted on the frame as at 26 and having one of its arms 27 acting on the upper side of spring member 20 which at the point of cooperation is provided with a cam surface. The other arm 28 of the lever 25 is provided with a finger 29 entering a lateral opening 30 in a sleeve 31 which surrounds the shaft 13, being fixed against endwise movement by means of a shoulder 32 formed on the shaft and the lower end of the knob 12. This sleeve 31 is mounted on the shaft 13 so as to be freely rotatable thereon and is sufficiently rugged to withstand wear.

In the particular form of mechanism illustrated there is shown a spring 40 provided at its free end 41 with a cam portion which rides a pin 42, the cam serving to maintain the lever 25 in one of its two positions.

The operation of the device is quite similar to the ordinary operation of winding or setting a watch, namely, when the stem is in its inward position such as shown in Fig. 2, rotation thereof will thru gear 17 wind the spring of the movement. When the stem is pulled to its outer position as shown in Fig. 1, the gears 15 and 16 will be in mesh and the gear 17 free so that rotation of the knob 12 will operate to set the hands.

In Fig. 7 is shown a small modification of the device already described. In this figure the sleeve 31a is in most respects similar to sleeve 31 except that the shaft 13 extends eccentrically thru the sleeve thus providing more stock on the side containing opening 30a so that a still more rugged device is provided.

In the modification shown in Fig. 8, the sleeve 31b is shown as provided with a pin 29B fixed therein and cooperating with an eye 30B in the end of the lever 28B. This is obviously the mechanical equivalent of the previously described form.

In Fig. 9 there is shown an assembly of stem and sleeve showing a minor difference over Figs. 1 to 5 in that shoulder 32 is shown as having a rounded or conical upper face 32C.

Now having described the invention and the

preferred embodiment thereof, it is to be understood that said invention is to be limited, not to the specific details herein set forth, but only by the scope of the claims which follow:

5 What I claim is:—

1. In a watch movement having a winding stem or post adapted to be moved out of normal winding position for setting, a shaft provided with shoulders, a rotatable sleeve between said shoulders and provided with a lateral opening, a clutch operating lever provided with means cooperating with said sleeve to move said lever when said shaft is moved longitudinally and means to fix said lever in winding or setting position.
- 15 2. In watch mechanism having a winding post adapted to be moved to permit setting, a clutch element, a lever for operating said clutch element to a plurality of positions, a finger on said lever, and a rotatable sleeve on said post having means cooperating with the finger on said lever and means to prevent longitudinal movement of said sleeve on said post.
- 25 3. In watch mechanism having a winding post adapted to be moved to permit setting, a clutch element, a lever for operating said clutch element to a plurality of positions, a finger on said lever, and a rotatable sleeve on said post having means cooperating with the finger on said lever and means to prevent longitudinal movement of said sleeve on said post, said sleeve being eccentric to said post.
- 30
4. A watch construction comprising a winding and setting stem, and a bearing sleeve held against longitudinal displacement on said stem, said sleeve having one or more recesses for the engagement of a setting lever and being free of the stem in respect to rotation.
5. A watch construction comprising a winding and setting stem having a fixed, inner shoulder and an outer, removable shoulder, and a bearing sleeve confined between said shoulders but free in respect to rotation of the stem and having one or more recesses for the engagement of a setting lever.
- 10 6. A watch construction, comprising, in combination with a setting lever, a winding and setting stem having a shoulder intermediate its ends and a crown applied to the outer portion of the stem, and a bearing sleeve confined on the stem between said shoulder and crown but free in respect to rotation of the stem, said sleeve and stem coacting with the setting lever.
- 15 7. In a watch construction, which includes a setting lever and a winding wheel, a winding and setting stem having a shoulder enlargement immediately above the winding wheel, a part applied to the outer portion of the stem, and a bearing sleeve confined between said part and said shoulder, said sleeve having one or more recesses for the engagement of the setting lever.
